UNITED STATES PATENT OFFICE.

JOHN S. PARK, OF ROCKPORT, INDIANA, ASSIGNOR OF THREE-FOURTHS TO
TAYLOR C. BASYE AND FERDINAND WEIL, BOTH OF SAME PLACE.

OILER.

SPECIFICATION forming part of Letters Patent No. 296,047, dated April 1, 1884.

Application filed February 6, 1884. (No model.)

To all whom it may concern:

Be it known that I, JOHN S. PARK, of Rockport, in the county of Spencer and State of Indiana, have invented a new and Improved 5 Oiler, of which the following is a full, clear, and exact description.

The object of my invention is to provide a simple, inexpensive, and effective device for oiling the cross-head guides of steam-engines, 10 more particularly; but the invention is applicable also to oiling the guides of other reciprocating parts of machinery.

The invention consists in an oiler having pivoted oiling-heads carrying oil cups or reservoirs, and a weighted stem to throw the oiling and wiping heads into contact with the friction-surfaces of the cross-head guides by the inertia and momentum of the parts on reversal of the motion at the limit of the stroke of the 20 cross-head in either direction.

The invention consists, also, in certain details of construction and combinations of parts of the device to adapt it to serve either with single or double cross-head guides, all as hereinafter fully described and claimed.

Reference is to be had to the accompanying drawings, forming part of this specification, in which similar letters of reference indicate corresponding parts in all the figures.

30 Figure 1 is a side elevation of my improvement as applied to the single-bar cross-head guide of a locomotive steam-engine. Fig. 2 is a plan view of the same in part; and Fig. 3 is a side elevation, partly broken away, of a modification of the improvement, and as applied to a double parallel bar cross-head guide.

Referring first to Figs. 1 and 2 of the drawings, A is the cross-head; B, the bar or guide on which the cross-head travels back and forth. C is the piston-rod connecting the cross-head with the piston in the cylinder D, and E is the connecting-rod leading to the engine-crank. All these parts may have any approved construction.

45 On any suitable base-plate, F, I fix three standards or posts, G G' G, G' being the center post, to which is pivoted the head H, which has a segment of gear-teeth, h, at each end, and a central stem, H', fixed at right angles to the head H, and carrying a weight, H², which preferably is adjustable along the stem, and may be held, when adjusted, by a set-screw, e.

On each side post, G, I pivot at g an arm, I, which carries at one end a segment-plate, I', having gear-teeth i, meshing with the teeth h 55 of the head H, and at the outside downwardly-bent portion of the arm I is fixed a plate, J, having a wiper or cushion, j, of any suitable soft fabric—such as sponge, felt, &c.—secured to its under side, to receive and distribute over 60 the face of the guide B the oil fed to it through a passage in the plate J from an oil-cup, K, of any suitable kind, carried on the back of the plate. The gears h i are intermeshed, so that a rocking of the weighted stem H' to 65 either side of a vertical line will raise one of the oiling-heads J j from and lower the opposite one to the guide-bar B.

In operation, as the cross-head A moves inward toward the cylinder D, the stem H' will 70 lie over to the left of a vertical line, and the right-hand oiler-head J j will bear on the guide B in advance of the cross-head A or its brass a, and after completion of the inward stroke, and on reversing for the outward movement, 75 the inertia of the weighted stem H', together with the forward momentum of the cross-head in its outward stroke, will cause the stem H' to shift over quickly to the right of the vertical line and lift the inward oiler-head J j and 80 lower the outer head J j upon the guide B and in advance of the moving cross-head, which are the positions of the parts shown in the drawings. At the extreme limit of the outward stroke, and on reversal for the inward 85 stroke, the stem H' will be shifted to the left, and the right-hand oiler will bear on the guide B in front of the cross-head, as first described, and these operations will be continued with the travel of the cross-head, the opposite heads 90 J j bearing always on the guide B in advance of the cross-head. The oiling-heads not only feed oil to the upper face of the guide, but act also to wipe from it any dust or grit, which would, if not removed, unduly wear the friction-surfaces. 95

I have shown the oiler base-plate F slotted at f, so as to pass beneath the heads of the nuts d, used to fasten the top brass, a, and take up the wear of the brasses; but the oiler may be 100 held to the cross-head in any other suitable manner.

In the modification shown in Fig. 3, in which I apply the same principle of rocking

- the opposite oiling-heads into contact with the guide-bars by the inertia and momentum of the parts on the reversals of stroke of the cross-head, I pivot to both sides of the cross-head A² a four-armed or suitable head, G², made hollow to communicate with an oil-cup, K², held thereon, and deliver the oil from the cup and through opposite hollow arms or tubes I² to perforated oiling-heads J², having oil-absorbing wipers j² suitably fixed around them, and entered by bending the tubes I² between the parallel side guide-bars, a' a', and the stem H³ is weighted adjustably at H⁴, sufficiently to overbalance the oil-cup K² to either side as the strokes of the cross-head are reversed. In the drawings the cross-head is moving to the left hand on the outward stroke, for example, and the left-hand head J² j² rests upon the lower bar a' to wipe and oil it, and the opposite or right-hand head J² j² rises against the upper bar a' to wipe and oil it, and on the reverse or rearward stroke the right-hand head J² j² will oil the lower bar a' in advance of the cross-head, while the left-hand head will oil the upper bar, as will readily be understood.
- The oil-cups shown may be substituted by recesses in the oiler-heads, forming reservoirs for the oil, and connecting by suitable passages with the wipers or pads of the heads.
- Having thus described my invention, what I claim as new, and desire to secure by Letters Patent, is—
1. An oiler for the guides of engine cross-heads and other reciprocating parts of machinery, constructed with a pair of opposite pivoted
- oiling-heads carrying or connected with an oil cup or cups, and having a weighted stem adapted to be thrown to either side of a vertical line for bringing the oiling-heads in contact with the guide bar or bars by the inertia and momentum of the parts on reversal of the motion at the limits of the stroke of the cross-head in either direction, substantially as shown and described.
2. In an oiler, the combination, with a weighted stem pivoted to the reciprocating cross-head, of an oiling-head actuated by the swing of the stem to either side, so as to bear the oiling-head on the cross-head guide in advance of the moving cross-head, substantially as shown and described.
3. The combination, in an oiler, and with the reciprocating cross-head A and guide B, of the pivoted head H, carrying a weighted stem, H', and pivoted arms I, swung by the stem and provided with oil cups or reservoirs and absorbent wipers J j, receiving the oil and distributing it on the guide, substantially as shown and described.
4. The combination, with the cross-head A² and its side guides, a' a', of the pivoted heads G², carrying oil cups or reservoirs and weighted stem H³, the hollow arms I², and the oiler-heads J² j², working between the guides a' a', substantially as shown and described.

JOHN S. PARK.
